DUAL ROCKER

Charles O. Boren, Sr., Dearborn, Mich.

Application May 13, 1950, Serial No. 9,919

Term of patent 3½ years

(CL. D15—6)

To all whom it may concern:

Be it known, that I, Charles O. Boren, Sr., a citizen of the United States, residing at Dearborn, Wayne County, Michigan, have invented a new, original, and ornamental Design for a Dual Rocker of which the following is a specification, reference being had to the accompanying drawing, forming a part thereof, wherein:

Fig. 1 is a perspective view showing my design for a dual rocker.

Fig. 2 is a front elevational view of my design for a dual rocker.

Fig. 3 is a top view of my design for a dual rocker.

Fig. 4 is a side elevational view of my design for a dual rocker.

I claim:

The ornamental design for a dual rocker, as shown.

CHARLES O. BOREN, SR.
